Patented Jan. 1, 1918.

UNITED STATES PATENT OFFICE.

HARRY C. AYERST, OF SEATTLE, WASHINGTON, ASSIGNOR TO SANITARY PULP PRODUCTS COMPANY, OF SEATTLE, WASHINGTON, A CORPORATION OF WASHINGTON.

MACHINE FOR LIQUID-PROOFING VESSELS.

1,252,315.

Specification of Letters Patent. Patented Jan. 1, 1918.

Application filed December 29, 1914. Serial No. 878,480.

To all whom it may concern:

Be it known that I, HARRY C. AYERST, a citizen of the United States, residing at Seattle, in the county of King and State 5 of Washington, have invented certain new and useful Improvements in Machines for Liquid-Proofing Vessels, of which the following is a specification.

This invention relates to machines or apparatus which are utilized to render liquid-proof vessels, bottles or other receptacles formed of a perforate or absorbent material.

Its object is to produce an efficient and rapidly operating machine of this character.

15 The invention consists in devices whereby a water-proofing substance, such as paraffin, is supplied to a receptacle for coating the internal surfaces thereof, means for removing any surplus of such substance from the 20 receptacle, and means for automatically regulating the movements of the receptacles during and subsequent to their being made water-proof.

The invention further consists in the novel 25 construction and combination of parts, as will be hereinafter described and claimed.

In the accompanying drawings, Figure 1 is a longitudinal vertical section of a machine embodying the present invention. 30 Fig. 2 is a view of the same, partly in plan and partly in horizontal section, the section being taken through 2—2 of Fig. 1. Fig. 3 is a horizontal sectional view through 3—3 of Fig. 1. Fig. 4 is a detail sectional view 35 through 4—4 of Fig. 2.

The machine herewith illustrated is designed, more particularly, for applying a water-proofing substance to the interior of bottles, although it may be similarly used 40 for other receptacles, such as pails or cuspidors.

Referring to the drawings, the numeral 5 designates the top or table of the machine frame, and 6 is a conveyer belt whereby the 45 articles to be treated are brought to one end of said table. Included in said frame is an upright post 7 having secured to its upper end a non-rotatable cylindrical bowl 8 provided in its periphery with a port 9, Fig. 3. 50 Superposed upon said bowl is a cover which may be constituted by the flange 10 of a pipe 12 whereby molten paraffin is supplied to the bowl.

Rotatable upon the post 7 is the tubular stem 13 of a casing 14 which is bored to receive said bowl. In the peripheral wall of the casing 14 is a plurality of spaced openings for the reception of discharge spouts 15.

16 represents a gland for holding a packing ring 17 to prevent any leakage at the upper edge of said casing. At its lower end the stem 13 is provided with a spur-gear wheel 18 which is engaged by a toothed pinion 19 mounted upon a shaft 20. This shaft is driven by means of a chain 21 and 65 sprocket wheels 22 from a power-driven shaft 23.

At a distance above the table 5, the stem 13 is provided with a disk-like flange 24 of a radius sufficient to extend over the conveyer-belt 6. This disk or carrier, as it will be hereinafter designated, is provided in its circumference with a series of recesses 25 which are disposed beneath the respective spouts 15.

61 represents a guide positioned above the belt 6 for directing the bottles conveyed thereupon into positions to be engaged within the carrier recesses 25, as they are successively presented in the rotating of the carrier in the direction indicated by arrow A in Fig. 2. The bottles are thereupon revolvably moved from the belt and upon the table by the carrier.

On or about the time a bottle is thus carried onto the table, the opening in the casing 14 of the spout above this bottle traverses the bowl port 9 resulting in a quantity of paraffin discharging through the spout into the bottle.

In the further rotation of the carrier, the bottle is withdrawn from the table, then inverted to allow the paraffin to flow over the throat and mouth of the bottle, pour out the surplus, and finally deposit the inverted 95 bottle upon a rack or conveyer.

The mechanism by which these actions are accomplished will now be described.

26 represents a box which is secured to or formed on the upper end of an upright 100 shaft 27 which is journaled in a block 28 secured to the machine-frame. Extending from the box 26 is a curved arm 26' provided with a socket for the stalk 29 of a concave jaw 30. The outer end of this stalk 105 engages a spring 31 having one end fastened

to said arm and tending to push the jaw to the extent of its movement toward the box 26. Within the referred to arm socket the stalk 29 is provided at diametrically opposite sides with grooves 29¹ and 29² to successively receive a spring-pressed ball 32 which serves to yieldingly hold the jaw 30 in normally horizontal positions.

Opposing this jaw is a second jaw 33 having a stalk or rod 34 which extends axially through a cylindrical chamber 26² provided in the box 26 and to a distance therebeyond.

Near its extremity remote from the jaw 30 the rod 34 carries an arm 35 upon which are rotatably mounted rollers 36 and 37 arranged to respectively track against the outer edge 38¹ and the under-side 38² of a bar flange 38 which constitutes a cam. This cam is provided with a central curved portion concentric to the axis of the shaft 27 which serves as a swivel for the box 26 while the end portions 39 and 39¹ of the bar are directed outwardly, as shown in Fig. 2.

40 represents a helical spring acting between an end of said box chamber and a collar 41 provided on the rod 34 whereby the latter is caused to push the jaw 33 toward the other jaw, subject to the influence of the cam.

30 Splined to the rod 34 is a toothed gear-wheel 42 which engages an arcuate rack 43 provided on the block 28 and serves to effect the turning of the rod and the jaw 33 when the box 26 is turned on its swivel. The gear-wheel 42 is, however, secured against axial movement by means of a stud 44 extending into an annular groove provided on the wheel hub 42¹.

The shaft 23 is provided with a crank-arm 45 which is operatively connected by a rod 46 with a crank-arm 47 provided on the shaft 27. The crank-arms are proportioned so that each revolution of the arm 45 will reciprocate the other arm through an arc somewhat less than 180° to afford corresponding movements to the box 26 and the parts carried thereby.

48 represents a receptacle into which the surplus paraffin is poured from the bottles 50 and 49 is a rack whereupon the bottles are deposited in inverted positions.

The operation of the invention is as follows:

The paraffin in a liquid form is supplied 55 to the bowl 8. The bottles, as B, are fed into the recesses 25 of the carrier 24 as they are revolubly moved over the belt 6. In being conveyed by the carrier and when, with a bottle in about the B¹ position, the 60 respective spout 15 passes the port 9 in the bowl 8, a charge of paraffin will be delivered through such spout into a bottle. When a bottle is carried into the position indicated by B², Fig. 2, the jaw 33 will be at a distance from the other jaw 30 sufficient for

the bottle to enter the space therebetween. Immediately after this occurs, the crank-arm 45 is being revolved by its shaft 23 to impart motion, through rod 46 and the crank-arm 47, to the shaft 27 so as to rotate 70 the box 26 on the axis of the last-named shaft so that the rod 34 will be swung in the direction denoted by arrow C.

In this movement the spring 26 asserts its power to cause the roller 36 to track 75 against the opposing edge of the cam flange so that when the roller has reached the concentric portion 38¹ thereof, the jaw 33 is thrust against the bottle and pushes the same against the other jaw 30 in opposition 80 to the spring 31.

Meanwhile, the box 26 is turning and cooperates with its arm 26¹ to carry the bottle in the direction indicated by arrow E. During such action the gear wheel 42 is affected 85 by the rack 43 to give rotary motion to the jaw 33 and also, through the medium of the bottle, affords like motion to the jaw 30.

At the end of its travel, the jaws have been turned over to invert the bottle and 90 thereby empty the surplus paraffin into receptacle 48. During the last part of the above described travel, the roller 36 encounters the portion 39 of the cam, resulting in the withdrawal of the jaw 33 and 95 thereby deposits the bottle in an inverted position on the rack, as indicated by broken lines b in Fig. 2. After this is attained, the crank-arm acting through the rod 46 and crank-arm 47, turns the box 26 and the 100 parts which are carried thereby into the positions in which they are represented in Fig. 2.

In turning the jaw 30, the spring-pressed ball 32 is pushed by the rotating stalk 29 105 from one groove, as 29¹, Fig. 4, at the beginning of such rotary movement, and enters the other groove 29² at the termination thereof, thus arresting the stalk and its jaw after making a half-rotation, where it remains until restored to its original position in the inverting of the next bottle, and so on.

Having described my invention, what I claim, is—

1. In a machine of the class described, 115 the combination with a rotary bottle-carrier, and means for supplying a liquid-proofing material to bottles in their orbital travel with the said carrier, of means for removing the bottles from said carrier, said bottle-removing means including devices whereby the bottles are inverted subsequent to being taken from the carrier.

2. In a machine of the class described, 125 the combination with means for delivering a charge of liquid-proofing material into a bottle, of devices for pouring the surplus material from the bottle, and then delivering the bottle in an inverted position.

3. In a machine of the class described, a 130

liquid receptacle, a rotary carrier, means
movable with said carrier for delivering
charges of the liquid-proofing material into
articles carried by the carrier during the
5 operation of the latter and means to invert
said articles successively to pour surplus
material therefrom.

Signed at Seattle, Wash., this 16th day of
December, 1914.

HARRY C. AYERST.
